FRICTION ADJUSTMENT FOR LEVERS

Edwin F. Pain, Corry, Pa., assignor to Aero Supply Mfg. Co., Inc., Corry, Pa.

Application October 18, 1943, Serial No. 506,743

8 Claims. (Cl. 74—531)

This invention relates to a friction adjustment for levers mounted on a common pivot.

In throttle controls or quadrants used for regulating airplane engines, a plurality of levers are rockably mounted on a common pivot and heretofore the frictional resistance of these levers has been regulated by means of a single tensioning device. This prior tensioning device has not been entirely satisfactory because of the fact that the same frictional resistance was placed on all of the levers, whereas it is desirable that there be a differential frictional resistance on certain ones of the levers. It is therefore an object of this invention to provide in combination with a throttle control or quadrant for airplanes concentrically arranged and independently tensionable friction means whereby certain ones of the levers forming the control may be adjusted as to tension different from the other levers. In this way the pilot may adjust the tension on one or more levers so that they may be rocked with only slight pressure, whereas others of the levers may be adjusted so that heavier pressure must be exerted to rock the same.

Another object of this invention is to provide an adjustable friction means for a plurality of rock levers which are mounted on the same pivot wherein one or more of the levers may have a fixed adjustment as to friction and the remaining lever or levers may be easily and quickly adjusted by rotation of a hand wheel or nut, so that the remaining lever or levers may have more or less friction applied thereto than the first lever.

With the foregoing objects and others which may hereinafter appear the invention consists of the novel combination, construction and arrangement of parts as will be more specifically referred to and illustrated in the accompanying drawings wherein is shown an embodiment of the invention, but it is to be understood that changes, modifications and variations may be resorted to which fall within the scope of the invention as claimed.

In the drawings:

Figure 1 is a detail front elevation of a throttle control or quadrant having an adjustable friction means embodied therein,

Figure 2 is a sectional view taken on the line 2—2 of Figure 1,

Figure 3 is a sectional view taken on the line 3—3 of Figure 1,

Figure 4 is a sectional view taken on the line 4—4 of Figure 3,

Figure 5 is a sectional view taken on the line 5—5 of Figure 3,

Figure 6 is a sectional view taken on the line 6—6 of Figure 3,

Figure 7 is a sectional view taken on the line 7—7 of Figure 3,

Figure 8 is an enlarged fragmentary vertical section through the central portion of the device, and

Figure 9 is a diagrammatic view showing the differential friction adjustment structure.

10 Referring to the drawings, the numeral 10 designates generally a quadrant which is formed of a frame 11a having levers 11, 12 and 13 pivotally mounted therein. The lever 11 is the main throttle lever and is adapted to be connected to the throttle regulating means for an airplane engine. The lever 12 may be a mixture adjusting lever connected to the carburetor for adjusting the mixture of fuel, and the lever 13 is a manually adjustable lever connected to the propeller pitch adjusting mechanism.

15 The three levers are rockably mounted on a common pivot which is in the form of a cylindrical member 14. The member 14 has a head or block 15 threaded into one end thereof which is secured by fastening members 16 to the rear of the frame 11a. The forward end of the cylindrical pivot member 14 is formed with a plurality of circumferentially spaced apart tongues 17 forming spaces 18 therebetween. A plate or head 19 which is formed with tongues or fingers 20 is adapted to engage in the end of the pivot member 14 opposite from the head 15, the tongues 20 projecting through the openings or slots 18 between the fingers 17. The plate or head 19 is adapted to seat in a rabbet or annular recess 21 which is formed in the inner side of the front frame member 22.

20 The pivot member 14 has mounted thereabout adjacent the rear portion thereof a cylindrical sleeve 23 which at its forward end is formed with a plurality of circumferentially spaced apart tongues or fingers forming slots 25 therebetween. A second sleeve 26 is slidably mounted on the pivot member 14 forwardly of the sleeve 23, the latter sleeve bearing at its rear end against the rear frame member 21. The sleeve 26 at its rear end is formed with a plurality of circumferentially spaced apart tongues or fingers 28 forming slots 29 therebetween. The tongues or fingers 28 are of

25 a width such that they will slidably engage in the slots 25 of the rear sleeve 23. The hub of the main throttle lever 11 is rockably mounted on the periphery of the rear sleeve 23 and is spaced forwardly from the rear frame member 21 by 30 means of a pair of combined spacer and friction

elements 30 and 31. A friction ring 32 is interposed between the spacer and friction member 31 and the rear side of the hub of the lever 11. A spacer 33 is mounted on the sleeve 23 on the forward side of the lever 11 and a friction ring 34 is interposed between the rear end of the spacer 33 and the forward side of the hub of the lever 11. The spacer 33 has secured thereto an electrical coupling element 35 by means of which wires may be extended into the interior of the hollow pivot member 14 and then extended upwardly through an arcuate slot 36 formed in the pivot member 14 and another arcuate slot 37 registering with the slot 36 which is formed in the sleeve 23. The wires are then extended upwardly along the length of the lever 11 to the combined knob and switch 38 which is mounted on the upper end of the lever 11.

A pressure ring 39 is slidably mounted on the sleeve 33 and is formed on the inner edge thereof with a plurality of inwardly projecting lugs 40 projecting into the slots 25 between the tongues 24. The tongues 28 of the sleeve 26 are adapted to engage the lugs 40 so that endwise pressure or tension placed on the sleeve 26 will communicate this pressure to the lugs 40, the pressure ring 39, and through the spacer 33 this pressure will be communicated to the friction rings 34 and 32. A ring 41 is slidably mounted on the pivot member 14 and bears at its rear side against the forward end of the sleeve 26.

The ring 41 is tensioned by means of a resilient spider 42 which has the arms 43 thereof loosely engaging in slots 44 formed in the pivot member 14 rearwardly of the slots 18. The spider 42 is mounted on a centrally disposed bolt 45 which is threaded at its rear end in the plate 15 and extends centrally through the pivot member 14. A pressure plate 46 of disc shape is slidably mounted within the pivot member 14 and slidably mounted on the bolt 45, bearing at its rear side against the forward side of the resilient spider 42. A sleeve 47 is slidably mounted on the bolt 45 and bears at its rear end against the plate 46.

A hand wheel or nut 48 is threaded on the forward end of the bolt 45 and a washer 49 is interposed between the rear side of the wheel or nut 48 and the forward end of the sleeve 47. Adjustment endwise of the wheel or nut 48 will vary the tension applied to the sleeve 26 through the resilient spider 42 and thereby provide for the desired friction being applied through the pressure ring 39, the spacer 43 to the friction rings 32 and 34.

The lever 12 is rockably mounted on the sleeve 26 forwardly of the pressure ring 39 and friction washers or rings 50 and 51 are disposed on the rear and forward sides respectively of the hub of the lever 12. A rear ring 52 is interposed between the rear friction ring 50 and the forward side of the pressure ring 39. The ring 52 is provided with a plurality of inwardly projecting lugs 53 which loosely engage in the slots 29 of the sleeve 26. A movable spacer ring 54 which is L-shaped in transverse section is slidably mounted on the sleeve 26 forwardly of the friction ring 51. The spacer 54 is of inverted L-shape and loosely encloses the pressure ring 41 for the main lever 11.

Friction rings or washers 55 and 56 are disposed on the rear and forward sides of the hub of the lever 13, the friction ring 55 bearing against the forward end of the spacer ring 54. A lever tensioning resilient spider 57 is slidably mounted on the pressure sleeve 47 and has the arms 58 thereof projecting through the

slots 18 in the central pivot member 14. The arms 58 of the spider 57 bear against the forward friction washer or ring 56 and the spider 57 is tensioned so as to apply the desired friction on the levers 12 and 13 by means of a cylindrical nut 59 which is threaded through the head or plate 19 and loosely engages about the sleeve 47. When the nut 59 is adjusted inwardly to tension the spider 57, the latter will move the levers 12 and 13 rearwardly a slight distance and against the rear spacer ring 52. This latter ring upon rearward movement thereof will have the inwardly projecting lugs 53 thereof bear against the forward ends of the fingers or tongues 24, thereby stopping the rearward movement of the ring 52. In the drawings, there is disclosed in exaggerated form a relatively wide space between the rear sides of the lugs 53 and the forward ends of the fingers 24. In actual practice, this space is normally very slight so that the lugs 53 will only have a very small rearward movement to effect engagement of these lugs with the forward ends of the fingers 24. In order to provide a means whereby the hand wheel 48 may not be rotated off of the bolt 45, I have provided a limit nut or stop 60 which is threaded and pinned or otherwise firmly secured on the forward end of the bolt 45.

In the use and operation of this throttle control or quadrant, the nut 59 may be adjusted by means of a wrench or the like to apply the desired friction to the two levers 12 and 13. The pilot of the plane may readily adjust the friction on lever 11 by turning the wheel or nut 48 inwardly. Inward adjustment of the nut or wheel 48 will move the sleeve 47 inwardly, the latter moving the plate 46 and putting the spring spider 42 under desired tension. Application of tension on the spider 42 will cause pressure to be applied to the lever 11 through the ring 41, sleeve 26, fingers 28 on the sleeve 26, lugs 40 on the ring 39, and pressure on the ring 39 will apply pressure to the spacer 33 from the latter to the friction washers 32 and 34 between which the hub of the lever 11 is rockably mounted. It will be apparent from the foregoing that any desired friction may be applied to the main lever 11 which may be more or less or equal to the friction applied to the levers 12 and 13. While the nut 59 is disclosed as being a plain nut which may be engaged by a wrench or the like, it will be obvious that a handle or second hand wheel may be secured to the nut 59 so that the latter may be easily and quickly adjusted to provide the desired friction on the secondary levers 12 and 13.

What I claim is:

1. In combination, a pair of rock levers, a common hollow pivot for said levers, a sleeve slideable endwise on said pivot and disposed within the hub of one of said levers and movable axially of said hub, means on said pivot engageable with said sleeve upon endwise movement of the latter within the hub of said one lever for applying frictional resistance to the other of said levers, means for moving said sleeve endwise, and means partly carried by said pivot and stationary relative thereto and partly carried by said sleeve and slideable on the latter for applying frictional resistance to said one lever.

2. The combination as set forth in claim 1 wherein said second and third means are disposed at only one end of said pivot.

3. In combination, a pair of rock levers, a common hollow pivot for said levers, a sleeve on said

pivot engaging within the hub of one lever and immovable endwise, said sleeve having spaced fingers at one end, a second sleeve on said pivot engaging within the hub of the other lever and movable endwise on said pivot, spaced fingers carried by said second sleeve engaging between the fingers of said first sleeve, means about said first sleeve engaging in the spaces between the fingers of said first sleeve and engageable with the fingers of said second sleeve upon endwise movement of the latter in one direction to apply frictional resistance to said one lever, and means for moving said second sleeve endwise in the direction of said first sleeve.

4. The combination as set forth in claim 3 which includes means independent of said first and second means for applying frictional resistance to said other lever.

5. The combination as set forth in claim 3 which includes means independent of said first and second means for applying frictional resistance to said other lever and said second and latter means being disposed at one end of said pivot.

6. In combination, a pair of rock levers, a common pivotal mounting for said levers, means for applying frictional resistance to the rocking of one of said levers, and a second means for applying frictional resistance to the rocking of the other of said levers, one of said means being disposed concentrically of and slidably interiorly of the other means, the endwise position of one lever remaining constant upon adjustment of the other lever, said first and second means projecting from one end of said mounting, and adjustable from a position adjacent said one end of said mounting, said first means including a stationary sleeve, an endwise movable sleeve confronting said stationary sleeve, an element engageable with and movable by said movable sleeve for applying frictional resistance to one lever independent of the frictional resistance of the other lever, said other lever being rockable on said movable sleeve and said

second named means including a stationary part abutting said stationary sleeve and parts adjustable endwise along said movable sleeve for applying independent frictional resistance to said other lever.

5 7. In combination, a pair of rock levers, a common hollow pivot for said levers, a sleeve slidable on said pivot, means at one end of said pivot for moving said sleeve endwise, means engageable with said sleeve and with one of said levers for applying frictional resistance to said one lever upon endwise movement of the sleeve in one direction, a stationary member about said sleeve between said levers and forming a fixed abutment 10 for the other of said levers, said sleeve movable within said stationary member, and means partly slidable on said sleeve engageable with said other lever for frictionally holding said other lever against said stationary member.

15 8. A friction applying means for a pair of rock levers having a common pivotal mounting comprising a cylindrical stationary sleeve about said mounting and upon which one of said levers is rockable, a fixed annular abutment about said sleeve against which one side of said one lever is adapted to engage, a second sleeve slidable on said mounting, a fixed second annular abutment having means engaging against the inner end of said first sleeve whereby said second abutment will be held against endwise movement, said other lever being positioned at one side of said second abutment, endwise movable means carried by said first sleeve and non-rotatable relative thereto, and engageable with said second sleeve, for frictionally 20 resisting rocking of said first lever, pressure applying means engageable with said second sleeve to thereby hold said endwise movable means under predetermined pressure, and a second pressure applying means for placing said second lever under predetermined frictional resistance.
